ATTORNEY

UNITED STATES PATENT OFFICE

MERWYN B. LINTON, OF CHICAGO, ILLINOIS

GREASE GUN CARTRIDGE

Application filed December 2, 1927. Serial No. 237,264.

This invention relates to containers, an object being to provide a container which may be utilized to hold grease and other materials, so as to provide a grease cartridge which may be readily inserted in a gun to permit of loading or filling the gun without the usual smearing of grease over the hands and clothing of the user.

Another object of the invention is the provision of a grease gun cartridge in which the container is sealed against air and leakage so that the grease will not escape or become hard, yet may be readily opened, the closures at the ends of the cartridge being secured in such manner as to permit of their convenient removal.

Another object of the invention is the provision of a grease gun cartridge which is especially adapted for use with a grease gun forming the subject matter of my co-pending application.

With the above and other objects in view, the invention further includes the following novel features and details of construction, to be hereinafter more fully described, illustrated in the accompanying drawings and pointed out in the appended claims.

In the drawings:—

Figure 1 is an elevation of the cartridge. Figure 2 is a plan view of one of the closure caps.

Figure 3 is a section on the line 3—3 of Figure 1.

Figure 4 is a fragmentary section taken substantially on the line 4—4 of Figure 1.

Referring to the drawings in detail wherein like characters of reference denote corresponding parts, the invention as shown comprises a cylindrical container 10 which may be formed of any suitable material, such as metal, either stiff or pliable. This container is provided at one end with an outwardly disposed flange 11 which extends circumferentially, and this end of the container is closed by a closure cap 12. It will be understood that the flange 11 may be used as a means to permit gripping by or contact with an extracting device. The cap is provided with a crimped flange 13, the free edge of which extends longitudinally and

inwardly over the flange 11 so as to provide an inwardly offset gripping portion in the form of a spring detent 14. The extremity of the flange 13 is outwardly offset as shown at 15. As plainly shown in Figure 4 of the drawings, the inwardly offset portion 14 which engages over the edge of the flange 11 will grip the flange 11 and securely hold the closure cap 12 in place. By means of pressure against the outwardly offset portion 15 of the closure cap flange, the said closure cap flange may be readily disengaged from the container flange 11 for the ready removal of the closure cap.

The opposite end of the container 10 is provided with a closure cap 16. This cap is crimped over the edge of the container as shown at 17 so as to provide a frictional engagement between the cap and container. The free edge of the cap is offset as shown at 18 so as to be spaced from the container and permit of the insertion of a suitable tool or other member to spread the free edge of the closure cap and disengage the cap from the container so that the cap may be readily removed.

Preferably, the container has slidingly mounted thereon an annular member which includes a cross sectional wedge-shaped ring 19 from which extends an annular flange 20. The container which is adapted to be filled with grease, is adapted to be inserted within the barrel of a grease gun or other receptacle, a portion of the receptacle or gun being indicated by dotted lines at 21. Prior to the insertion of the cartridge in the gun or receptacle, the annular member is forced outward so that the flange 19 engages behind the offset portion 18 of the closure cap 16. This portion of the closure cap is thus spread or forced outwardly from the container 20 so as to relieve frictional engagement between the closure cap and container and permit of the ready removal of the cap. The container is then inserted within the barrel or receptacle 21. As the container is forced inward, the outwardly offset portion 15 of the cap 12 engages the adjacent end of the receptacle 21, so that the latter acts to spread the flange of the closure cap 12 outward and disen-

gage the inwardly offset portion 15 of the closure cap flange from the flange of the container. The cartridge is then ready for use.

5 The invention is susceptible of various changes in its form, proportions and minor details of construction and the right is here-
in reserved to make such changes as properly fall within the scope of the appended
10 claims.

10 Having described the invention what is claimed is:—

1. A cartridge for grease guns and the like comprising a tubular container open at each end, a removable closure for one end of the container, means providing a frictional engagement between said closure and container, an offset flange extending around the periphery of the closure and spaced from the container for engagement by a spreader element, a removable closure for the opposite end of the container, and means comprising a slidable ring carried by the container between the ends thereof and movable into engagement with said first-named closure and adapted to disengage the same.

2. A cartridge for grease guns and the like comprising a tubular container open at each end, a removable closure for one end of the container, means providing a frictional engagement between said closure and container, an offset flange extending around the periphery of the closure and spaced from the container, a cross sectional wedge-shaped ring slidable upon the container to engage the flange and spread the latter to facilitate removal of said closure, and a removable closure for the opposite end of the container.

3. A cartridge for grease guns and the like comprising a tubular container open at each end, a circumferentially disposed flange extending from one end of the container, a flanged closure for said end, means carried by the closure flange for removable engagement over the container flange, means extending from the closure flange to engage a receptacle to spread the closure flange and facilitate the removal of the closure, a closure for the opposite end of the container, and a ring carried by said container and having an annular portion of wedge shaped cross section, said portion being movable into engagement with said last named closure and adapted to disengage the same.

5 4. In a device of the class described, a lubricant container adapted to be inserted into the barrel of a lubricant gun, a removable closure for the outer end of the container, means comprising a spring detent for releasably holding said closure in place, said detent being constructed and arranged to engage the barrel of the lubricant gun when the container is partially inserted therein, and to be released by a further movement of the container into the barrel of the gun.

5 In a device of the class described, a lubricant container adapted to be inserted into the barrel of a lubricant gun, a removable closure for one end of the container, means for releasably attaching said closure to said container, and means operated by contact with a part of the gun to release said attaching means as said container is inserted into said gun.

6. In a device of the class described, a lubricant container having an open end, a removable closure for said open end, a spring detent carried by said closure, and a re-entrant conformation on said container for receiving said detent.

7. In a device of the class described, a lubricant container adapted to be inserted into the barrel of a discharging device, the interior of said container being adapted to receive a discharging plunger without distortion, said container having an open end surrounded by a flange, a removable closure for said end, and a spring detent carried by said closure and engaging said flange.

8. In a device of the class described, a lubricant container adapted to be inserted into the barrel of a lubricant gun, said container having an open end surrounded by a flange, a removable closure for said end, and a spring detent carried by said closure and engaging said flange, said detent having a part operable by contact with the barrel of the gun to disengage said detent.

9. In a device of the class described, a container adapted to be inserted into the barrel of a discharging device, a removable closure of said container, an annular series of detents providing releasable engagement between said closure and said container, and means for automatically releasing said detents upon the insertion of said container into said barrel.

10. In a device of the class described, a lubricant container having an open end, a closure in tight frictional engagement with said end, a ring slidably carried on said container, said ring being constructed and arranged to be interposed between the closure and the container to loosen the frictional engagement.

11. In a device of the class described, a container having an open end, a closure for said end having a flange surrounding said opening and in tight frictional engagement therewith, an annular series of resilient outwardly turned portions at the outer edge of said flange, a slidable ring carried by said container, said ring having a portion constructed and arranged to be interposed between said container and said outwardly turned portions to loosen the frictional engagement.

12. In a device of the class described, a container having an open end, a removable cover for said end, means for holding said

cover in position on the open end of said container, the inside of said container being substantially cylindrical in formation and adapted to slidably receive a plunger for dis-
5 placing the contents of said container, said open end being entirely unobstructed when said cover is removed so that the plunger may be freely inserted or removed without distortion thereof, a receptacle for said con-
10 tainer, and means operable by inserting said container into said receptacle for releasing the cover from said container.

13. In a device of the class described, a substantially cylindrical container having an open end, a tight fitting closure for said opening, a ring carried by said container and mounted to freely slide thereon, said ring having a portion operable by engagement with said cover to expand the tight fitting
20 portion of said cover, whereby both ring and cover may be freely removed from said container.

14. A lubricant container adapted to be inserted in the barrel of a lubricant gun, said container being of substantial cylindrical formation, an opening at one end of said container through which the lubricant may be discharged, a detachable closure for the other end of said container, the inside of said container being substantially cylindrical in formation and unobstructed so that a plunger may be freely slideable into and out of said container, without deformation thereof, and a flange at the last mentioned end of said
35 container to serve as an extracting means.

In testimony whereof I affix my signature.
MERWYN B. LINTON.
